UNITED STATES PATENT OFFICE.

CARL B. IMRIE, OF NEW YORK, N. Y.

HEEL-SUPPORT.

1,380,477.

Specification of Letters Patent.

Patented June 7, 1921.

Application filed January 14, 1920. Serial No. 351,477.

To all whom it may concern:

Be it known that I, CARL B. IMRIE, a citizen of the United States, residing at New York, in the county of New York and State 5 of New York, have invented a new and useful Heel-Support, of which the following is a specification.

My invention relates to devices adapted to be worn inside the heel portion of a shoe 10 as a pad or cushion and as a support for the heel of the wearer.

The purpose of the invention is to provide a resilient or elastic cushion to relieve the shock usually experienced in walking on 15 hard surfaces, and to provide an adjustable support for the wearer's heel, to prevent or correct certain common foot troubles.

It is well known that the human foot, when in a weakened condition, does not retain its several bones in their proper anatomical positions. At such times the os calcis, or heel bone, has a tendency to tilt 20 forward, this being frequently accompanied by a lateral inward or outward rotation of that bone on its base. Continued lateral 25 tilting of the os calcis to either side results in uneven distribution of the weight of the body and consequent strain and discomfort, together with the unsightly and unhealthy 30 condition of uneven wearing down of the shoe heels.

My heel support is of such shape and contour as to correct any improper lateral tilting tendency of the os calcis and support 35 that bone in its proper anatomical position. It is also so constructed as to afford a longitudinal support to the os calcis or heel bone and to impart to the plantar surface of that 40 bone, forward of its superior tuberosity, a slight upward and rearward tilt. Means are provided for varying the degree of either the lateral correction or the longitudinal tilting applied to the os calcis, these means consisting of provisions for varying the 45 thickness of the heel support at or near its forward end, either throughout its entire width or on either side of its median line.

In order to meet the peculiar anatomical 50 needs of the feet of different individuals, I have provided means whereby the thickness of the device on either side of its longitudinal center may be altered at the will of the

wearer to change its contour relative to the heel bone, so as to cause the device to tilt or rotate the heel bone inwardly or outwardly 55 to a greater or lesser degree and to regulate the degree of upward tilting of that portion of the os calcis forward of its superior tuberosity.

To attain the above-mentioned objects I 60 have devised the improved heel support shown in the accompanying drawings, wherein—

Figure 1 is a perspective view of the heel support;

Fig. 2, a bottom plan view of the device, partly broken away;

Fig. 3, a side elevational view of the device from the left-hand side of Fig. 1;

Fig. 4, a sectional view on line 4—4 of Fig. 70 1, showing a modified arrangement of pocket 5 and opening 15;

Fig. 5, a side elevational view from the right-hand side of Fig. 1;

Fig. 6, a sectional view on line 6—6 of 75 Fig. 1;

Fig. 7, a detailed perspective view of the insert designed to be used in the central pocket shown in Fig. 1;

Fig. 8, a similar view of one of the inserts 80 designed to be used in the lateral pockets shown in Fig. 1;

Fig. 9, a perspective view of a modified form of heel support;

Fig. 10, a perspective view of a modified 85 form of insert designed to be used in the type of device shown in Fig. 9; and

Fig. 11, a perspective view of another modified form of heel support.

In the embodiment of my improvements 90 in a practical heel support, I employ a pad or cushion 1 of a shape and size to fit the inside of a shoe heel. This pad is preferably composed of smooth, flexible, leather but may be made of felt, canvas, or any other 95 suitable resilient material. It may be fashioned out of a single piece of material or built up of superimposed layers 1^a, 1^b, 1^c, of the same or different materials, and may be made either with or without a layer or layers 100 of rubber associated with the other materials or material. In one form of my invention I provide the pad or cushion with a layer of rubber, 1^a, on its bottom, the rub-

ber layer having an irregular or substantially star-shaped opening 15 through its center to increase the efficiency of the gripping action of the rubber in preventing the pad from slipping in the shoe, and to increase the elasticity of the pad in the region where the heel bone rests. This opening may be positioned as in Fig. 2 or under seat 16 of insert 5^a, as in Fig. 4.

10 In carrying out the purposes of the invention the pad or cushion is made considerably thicker at or near its forward portion than at its rearward portion. When placed in a shoe its upper surface slopes from its highest 15 portion toward both the forward edge and the rear portion. The pad is also thicker at one side edge than at the other, sometimes the right-hand edge being the thicker and sometimes the left-hand edge. Usually the 20 inner edge is thicker than the outer, as shown in Fig. 1, the pad illustrated in that figure being intended to be worn in the left shoe. As indicated in Fig. 1, the pad is longer along its outer side than on its inner side. 25 Its forward edge is oblique and the portion of the pad forward of the lateral pockets 3, 4, tapers gradually from the high parts in the region of the pockets down to the forward edge. The forwardly sloping portion 30 of the pad forms a support for the foot immediately below the cuboid bone, the provision of this support tending to cradle the foot and to aid in counteracting any tendency on the part of the wearer to run the 35 upper of the shoe over the sole on the outer side. It will of course be understood that the pad intended to be worn in the right shoe is similarly shaped, the contour of the pad being the reverse of that of the one 40 shown and described as designed for use in the left shoe, the pads being generally sold in pairs.

Due to the difference in thickness between the two sides or edges of the pad there is 45 a transverse slope to its upper surface from the thick to the thin edge which is provided for the purpose of correcting uneven wear on the one side or the other of the shoe heel. The longitudinal slope, as previously intimated, is designed to act upon the os calcis 50 to give its plantar surface forward of its superior tuberosity a slight upward and rearward tilt.

For the purpose of varying the degree of 55 transverse tilting of the os calcis, as well as the degree of longitudinal tilting, means are provided for increasing the thickness of the pad or cushion in its forward portion throughout its entire width or on one 60 side or the other of its longitudinal center. This is accomplished by means of inserts 12 adapted to be introduced into the body of the pad or attached to the pad on or near its upper surface. In the preferred 65 embodiment of the device I provide a pair

of lateral pockets 3, 4, in the forward part of the body portion of the pad, the pockets being of such shape as to receive and hold snugly the inserts. These pockets are positioned on either side of the plantar surface 70 of the os calcis forward of the superior tuberosity, and furnish an adjustable lateral support for that bone. The pockets are usually formed by an additional piece of resilient material stitched on or otherwise 75 secured to the upper part of the body portion of the pad or cushion 1, as indicated in dotted lines in Fig. 1, the lines of stitching in that figure defining the limits of the pockets and the extent to which the inserts 80 can be introduced thereinto.

In order to have the inserts in proper position to meet and support the os calcis, one of the pockets is usually made longer than the other and extended inwardly past the 85 longitudinal center of the pad. In the device as generally constructed for wear in the left shoe the pocket 3 will be longer than pocket 4; in the device for the right shoe pocket 4 will be longer than pocket 3. 90 The open ends of the pockets are shown in Fig. 1 at the sides of the pad, that figure illustrating the end of pocket 3 with an insert 12 therein. The pockets may, however, open to the rear instead of at the 95 sides, the rearward openings, shown at 13, 14, in Fig. 11, permitting the insertion or removal of the inserts without removing the pad from the shoe. In the form of heel support shown in Fig. 1 the pockets are 100 of such shape and arrangement as to form a recess between the edges of their abutting ends which serves as a seat for the reception of the heel bone. In other forms of my device this recess is omitted and the 105 pockets made to take the general shape of those designated 3^a, 4^a, in Fig. 11.

The upper wall of each pocket may be made somewhat thicker at its forward end than at its rearward end, gradually tapering toward the latter. The inserts are 110 preferably of soft elastic or resilient material, such as soft rubber, pressboard, leather or felt, and are substantially wedge-shape, being thick at the outer end at the center 115 and sloping off to a thin edge at the opposite end and also preferably tapering off transversely from the central longitudinal line to each side edge, although the transverse taper is not always necessary and may be omitted. 120

In the form of the device in which the pockets are of equal length the inserts are interchangeable; in the form shown in Fig. 1, wherein the pockets are of different lengths, the inserts are interchangeable to 125 the extent that all of the inserts made to fit the short pocket may also be used in the long pocket.

In many cases the desired results may be obtained by the use of a single pocket 130

3^b (Fig. 9) extending entirely across the width of the pad or cushion, the pocket in this form of device opening either at the side edges of the pad as shown in Fig. 9, 5 or on the surface of the pad at the rearward side, as in the case of the pockets shown in Fig. 11. In this single-pocket device it is desirable to use a reversible insert 2^b of the shape illustrated in Fig. 9, 10 or the insert may take the modified form 2^c, illustrated in Fig. 10, this insert being flat on one side (its bottom) and gradually increasing in thickness longitudinally from one edge to the other and transversely 15 throughout its length from each side to the middle. The supplemental central insert hereinafter described may be used with this type of device and a pocket to receive it is usually furnished, as shown in Fig. 9 and 20 designated 5^b. It should be noted, however, that the principal functions of this insert are performed by the special form of insert illustrated in Fig. 10 and that for this reason the supplemental pocket may sometimes be omitted altogether or the insert 25 therefor not used.

In the manufacture of my heel support it is not absolutely essential that the pockets be formed by separate pieces of material 30 to the body of the pad 1, as these pockets may be formed by means of slits or openings made in the pad, as shown in Fig. 11. These openings are usually made between adjacent layers of material, in which case 35 their limits are defined either by cementing or stitching in the same manner as where they are formed by a superimposed layer of material attached to the upper layer of the pad. The pockets formed as in Fig. 40 11 may open on the upper surface, rearwardly, as shown in that figure, or may open on the sides of the pad, as in Fig. 1.

As above stated, the inserts in the lateral pockets serve to wedge up the anterior end 45 of the os calcis. In the form of device illustrated in Fig. 1 the head of the os calcis is received in a recess 10 between the abutting ends of the lateral pockets. Directly beneath this recess is the supplemental pocket 50 5, formed in or attached to the heel pad 1 on or near its upper surface and in a plane immediately below that of the lateral pockets. This supplemental pocket is intended to receive an insert of special design. The 55 insert (5^a) is shaped to conform to the contour and to act as a resilient support for the shaft of the os calcis anterior of its superior tuberosity, being thickest near its forward rounded end, having a cup-shaped 60 depression 16 at about its center, and in general contour tapering abruptly forward and to each side and more gradually to a knife-edge at the rear, as indicated in Fig. 7. The cup-shaped depression is designed 65 to receive and form a seat for the shaft of

the os calcis. By the use of this insert not only is the anterior end of the os calcis lifted slightly upward, but it is possible to adjust the pressure on the plantar surface of that bone forward of its superior tuberosity. 70

What I claim as new is:—

1. A heel support comprising a pad or cushion having its bottom surface substantially flat and its top surface substantially flat at its rearward portion and sloping 75 transversely at its forward portion.

2. A heel support comprising a pad or cushion having its rearward portion substantially flat and its forward portion inclined longitudinally relative to said rearward portion, whereby the forward portion of the pad may support and give an upward and rearward tilt to the shaft of the os calcis. 80

3. A heel support comprising a pad or cushion thicker near its forward end than at its rearward portion throughout its width and of substantially uniform thickness at its rearward portion, and varying in thickness transversely at its forward portion. 90

4. A heel support comprising a pad or cushion having a substantially flat rearward portion and provided with a recess or pocket at its forward portion, and an insert in the pocket, said insert being thinned both laterally and longitudinally, whereby the os calcis may be tilted laterally on its base and an upward and rearward tilt imparted to the plantar surface of the os calcis forward of its superior tuberosity or seat. 100

5. In a heel support, a pad or cushion comprising a body portion provided with a laterally extending pocket or recess near its forward end for the reception of inserts, and a supplemental pocket or recess located substantially centrally of the upper part of the body portion for the reception of a supplemental insert. 105

6. In a heel support, a pad or cushion provided with a transverse pocket or recess adjacent to its upper surface near its forward end, an insert removably located in said pocket or recess, a supplemental pocket or recess positioned substantially centrally of the pad or cushion near its upper surface, 110 and an insert removably located in said supplemental pocket or recess to form a support for the plantar surface of the os calcis forward of its superior tuberosity. 115

7. In a heel support, a pad or cushion of substantially uniform thickness at its rearward portion, and means attached to said pad or cushion for varying the thickness of one side thereof relative to the other side at its forward portion. 120

8. In a heel support, a pad or cushion having its rearward portion of substantially uniform thickness and its forward portion inclined longitudinally relative to said rearward portion, and means attached to said 130

pad or cushion for varying the thickness of one side thereof relative to the other side at its forward portion.

9. In a heel support, a pad of resilient material adapted to form a cushion for the heel, means for varying the thickness of either side of the pad relative to the other side near the forward end of the pad, where-

by the os calcis may be tilted laterally in one direction or the other, and for adjusting the height of the surface of the forward part of the pad to vary the degree of upward and rearward tilting of the shaft of the os calcis forward of its superior tuberosity.

CARL B. IMRIE.
